UNITED STATES PATENT OFFICE.

THOMAS A. GALT, OF STERLING, ILLINOIS.

DESIGN FOR A HAND-SPRAYER.

SPECIFICATION forming part of Design No. 28,566, dated May 10, 1898.

Application filed March 15, 1898. Serial No. 673,983. Term of patent 7 years.

To all whom it may concern:

Be it known that I, THOMAS A. GALT, a citizen of the United States, residing at Sterling, in the county of Whiteside and State of Illinois, have invented and produced a new and original Design for Hand-Sprayers, of which the following is a specification, reference being had to the accompanying drawings, showing a part thereof.

Figure 1 exhibits my sprayer from the front in perspective. Fig. 2 is a front and rear elevation of the same.

The leading feature of my design consists in a reservoir A of the form of a triangular prism, having inserted in the intersection of two of its faces the cylinder B. The cylinder

B is provided with two circular end pieces B', having openings C. The back end of the reservoir A is furnished with the collared opening D and the front end with the small pipe E, as shown. The cylinder B is about twice the length of the reservoir A.

What I claim is—

The design for a hand-sprayer as herein shown and described.

Witness my hand this 12th day of March, 25 A. D. 1898.

THOMAS A. GALT.
